UNITED STATES PATENT OFFICE.

LIONEL LAURANCE, OF LONDON, ENGLAND.

CASE FOR SPECTACLES, EYEGLASSES, AND OTHER ARTICLES.

1,245,933.

Specification of Letters Patent.

Patented Nov. 6, 1917.

Application filed May 31, 1917. Serial No. 171,974.

To all whom it may concern:

Be it known that I, LIONEL LAURANCE, a subject of the King of Great Britain, residing at 14 Temple House, Temple Avenue, 5 London, England, have invented new and useful Improvements in Cases for Spectacles, Eyeglasses, and other Articles, of which the following is a specification.

My invention relates to improvements in 10 cases which are designed especially for containing spectacles and eyeglasses although they are also suitable for holding other articles.

Various types of spectacle and like cases 15 are known, among which may be mentioned the form in which the lid is secured to the body by a spring hinge which tends to hold it in the open position, a snap fastening being fitted to the front of the case to hold 20 the lid closed. With this construction when the fastening is released the lid flies open and can only be closed by being pressed down again onto the catch. In another well-known form of case a spring attachment is 25 provided whereby the lid is held either in the fully open or the fully closed position, into which position it is snapped by the action of the spring when it has been moved by the user past a dead point in the direction of opening or closing as the case may be. 30

Now, my invention has for its object to provide a case which shall combine the advantages of these two known types and to this end I provide a case, of the kind in 35 which the lid is snapped into the open and closed positions by a spring, with means for lifting the lid past the dead point when pressure is applied at a convenient point, at the back of the lid.

40 In a suitable arrangement for carrying out the invention the lid is provided with an arm or the like which projects below the hinge when the lid is closed and which is so arranged that pressure can be applied to it by the finger of the user in order to lift the lid upward until it passes the dead point of the snap-spring which then operates to snap and retain it open. For instance, the said arm may be an arm specially provided 45 for the purpose or that to which the snap-spring is attached and its inner or lower end may be arranged opposite a cut-away portion at the back of the body of the case, so that, when the lid is closed, the said end is 50 exposed and can be pressed by the finger. 55

In practice, the body and lid may be covered with the usual leather or like covering and this covering may be furnished with a thickening at the point which has to be pressed in order to form a kind of button. 60

To enable my invention to be fully understood I will describe it by reference to the accompanying drawing, in which:

Figure 1 is a plan view of one form of spectacle or eyeglass case made according to 65 the invention and shown closed.

Fig. 2 is a transverse section on the line 2—2, Fig. 1.

Fig. 3 is a view similar to Fig. 1 but showing the case opened, and 70

Fig. 4 is a view similar to Fig. 2 but showing the case in the open position.

a is the body of the case which is advantageously made of metal in the usual way and *b* is the lid thereof which is hinged 75 at *c* to the back of the body *a*. *d* is the spring which connects the body *a* and the lid *b* in such a manner that it holds the lid either in the closed position, as indicated in Figs. 1 and 2, or in the open position, as indicated in Figs. 3 and 4, this construction being well known. 80

e is the arm or the like which is secured to the underside of the lid, the said arm projecting below the hinge *c* when the lid 85 is closed, as shown in Fig. 2, and projecting, in this closed position, through the cut-away portion *f* formed in the back of the body *a* of the case, and terminating in a looped portion forming a finger engaging 90 member.

With this construction, as will be clearly understood, assuming that the lid is closed, as in Figs. 1 and 2, the case can be opened by pressure of the finger upon the looped 95 portion of the arm *e* so as to force the lid upward until the dead point of the spring *d* is passed, whereupon the said spring pulls the lid fully open and retains it in the open position. The lid is closed in the usual way 100 and is held in the closed position also by the said spring. The arrangement possesses the advantage that a person can open and shut the case by employing one hand only.

As above stated, the case may be made 105 either with or without a leather cover and in the drawing the cover is not shown. Where such a cover is employed then it passes around the projecting member *e* so as to completely inclose the whole of the 110

case and the said leather cover may then be furnished with a thickening at the point opposite the said member *e* or the equivalent so as to indicate the position at which pressure is to be applied.

It is to be understood that the means employed for lifting the lid may be varied in many ways, the essential feature of the invention being the combination in a spectacle 10 or like case of a spring device which snaps the lid into the open and closed positions when a certain dead point has been passed by the lid and of means, acting upon the back of the lid, for lifting the latter past 15 this dead point in the opening direction.

Claim:

A spectacle case comprising a body having an opening in its rear wall, a lid hinged to said body, a spring arranged within the case and connecting said lid and body for holding the lid in open and closed positions, and a finger engaging member secured to the underside of said lid and provided at its rear with a looped portion which extends through the body opening when the lid is in closed position, said looped portion being adapted to be forced forward for raising said lid.

LIONEL LAURANCE.
